UNITED STATES PATENT OFFICE

2,394,134

PLASTICIZED REFRIGERATOR CABINET

Russell W. Ayres, Evansville, Ind., assignor, by
mesne assignments, to Seeger-Sunbeam Corporation, a corporation of Minnesota

Application October 8, 1941, Serial No. 414,164

2 Claims. (Cl. 20—0.5)

My invention relates to refrigerator cabinets, and more especially to improvements in refrigerator cabinets employing plasticized unit slab structures.

In general, I form a domestic refrigerator cabinet, including a food compartment and an auxiliary compartment, which may serve as a machine compartment or as a vegetable bin, or both, and closures therefor, from slabs of more or less uniform thickness of insulating cellular material some of which are formed or bent to interfit to form practically the complete cabinet and present satisfactory outer and inner surfaces to the elimination of the outer shell and liner generally employed.

Among the features and objects of my invention are the following:

A form for the several component slab-like elements of the cabinet which requires a minimum number of pieces and joints (in fact, there is only one continuous joint in the food compartment apart from the door seal) to produce the food and auxiliary compartments required, and in which the interfitted pieces are so arranged that they provide adequate support for each other at what otherwise might be relatively weak regions and also so arranged that the cabinet as a whole is given an unusual degree of strength and rigidity;

Inexpensive slab elements, which may be formed by a thick layer of insulating cellular material, with plasticized surfaces;

Simple, inexpensive, and easily applied devices for holding the component parts together;

Elimination of the necessity of separate liners and outer jackets for the cabinet;

Employment of the plasticized surfacing of the cellular slab elements for any of—but preferably for a consolidation of all of—the three-fold functions of (a) sealing the cellular material against ingress of moisture, (b) reinforcing or strengthening the low structural strength cellular material to give the walls the proper rigidity and strength, and (c) forming outer and inner surfaces for the cabinet of sufficient hardness, smoothness and moisture impenetrability as to take the place of, and eliminate, the expensive enamel or porcelain-enamelled metal liners and outer jackets employed in conventional refrigerator cabinets;

A sealing strip for the limited joints between pieces on the interior of the cabinet, which is inexpensive, readily applied, and of texture and appearance conforming with that of the interior surfaces of the walls; and

Incidental hardware, such as feet, shelf supports, hinges, latches and the like, peculiarly suitable for incorporation in this type of refrigerator cabinet.

These and other objects and advantages of the invention are set forth in the following description and the accompanying drawing of a specific embodiment of my invention.

Referring to the drawing, of which there is one sheet:

Fig. 1 is a view partly in front elevation and partly in transverse vertical section of a refrigerator cabinet embodying my invention;

Fig. 2 is a section taken on the plane of the line 2—2 of Fig. 1; and

Fig. 3 is an enlarged section of a portion of the plasticized insulating material employed in the cabinet illustrated in Figs. 1 and 2.

Referring to the drawing in detail, a refrigerator cabinet 10 has a body portion which consists essentially of a combined side wall and top unit 11 which is in the form of an inverted U. A combined back wall and compartment bottom member 12, which may have the same structural characteristics as the body portion of the cabinet, is adapted to fit into the U-shaped side wall and top member to form a refrigerator compartment. A door 13 is mounted to close the open side of the refrigerator cabinet.

The combined side wall and top unit 11 has straight vertical side wall portions 14 and 15, and a transverse web portion 16 forming the top of the cabinet. The web portion 16 preferably is arched slightly as illustrated in Fig. 1 to provide a pleasing contour. The corner portions between the upper ends of the side walls and the web portion 16 preferably are curved on rather generous radii for the double purpose of permitting the insulating material comprising the side walls to be bent without rupture, and to improve the appearance of the finished product. The combined back wall and bottom member 12 has a vertically disposed straight back wall portion 17, the upper end of which is shaped to fit within the upper end of the combined side wall and top unit 11, the lower end of the member 12 being bent forwardly at substantially right angles to provide a bottom 18.

A plurality of tie rods 19 are threaded through oppositely positioned pairs of holes in the side walls 14 and 15 of the unit 11 and through registering holes provided transversely of the combined back wall and bottom unit 11. Each of the tie rods 19 is provided with nuts 20 threaded on the ends thereof, the nuts 20 being

drawn down to force the side walls 14 and 15 tightly against the lateral edges of the combined back wall and bottom member 12.

Enlarged recesses 21 are provided in the side walls at the outer ends of each of the rod-receiving openings to receive the nuts 20, and these recesses 21 are sealed with matching plugs 22 after the nuts 20 have been drawn down into tightly secured position.

A plastic fillet 23 is fitted over the entire length of the joint between the members 11 and 12, the plastic material used for this fillet 23 having tight sealing adherence to the plasticized surfaces of the members 11 and 12. Thus, a single continuous fillet seals all of the joints of the compartment, save for the door seal.

A plurality of shelf support pins 26 may be provided on the side walls 14 and 15, these pins as illustrated each comprising a plastic button portion 27 (see Fig. 3) with a central metal core 28. The metal core 28 projects beyond the base of the button portion to penetrate the insulating material comprising the walls of the cabinet. The pins thus obtain a dual support, both from the adhesion of the plastic button portion 27 to the cabinet wall, and the penetration of the metal core 28 into the body of the wall itself.

The door 13 may be of conventional construction, but preferably is of the same type of construction as the cabinet 10. As illustrated, the door 13 comprises a panel or slab of insulating material having a plasticized shell of limited penetration, coating and impregnating the entire exposed surface area of the door in the same manner as the body members 11 and 12. The door 13 may be mounted on the cabinet 10 as by means of suitable hardware including a latch 24 and hinges 25.

A resilient sealing strip 30 is secured to the rear face of the marginal portion of the door 13 in a position to have compressive engagement, when the door is closed, with the frontal exposed edges of the members 12, 14, 15 and 16 comprising the bottom, sides and top respectively of the refrigerator storage compartment.

The side walls 14 and 15 of the member 11 extend downwardly below the bottom 18 of the combined back wall and bottom member 12 to form the side walls of a compartment which may be used for non-refrigerated storage space, or may be used to house suitable refrigerating mechanism, not illustrated. A base member 31 may be of suitable material such as formed sheet metal or plasticized insulating material and, as illustrated, extends the entire width of the cabinet, so that the lower ends of the side portions 14 and 15 may rest upon the base member 31.

The base member 31 may be joined to the side walls 14 and 15 as by combined bolt and leg levelers 32. Each leg leveler 32 has a threaded shank portion 33 which passes through an opening in the bottom 31 and through passages provided in the side walls 14 and 15 in registry with the openings in the bottom member 31. An enlarged recess 34, opening into the inner side of the wall, is provided at the upper end of each passage in the side walls 14 and 15, to receive a nut 35 which is threaded onto the shank 33 to secure the base member 31 closely against the bottom edges of the sides 14 and 15.

The lower end of each shank 33 may be provided with an enlarged head portion 36 which is threaded exteriorly and has threaded thereon a cup-shaped leg leveler 37. An enlarged recess

38 is provided at the lower end of each of the openings for the shanks 33 to receive the leg leveler 37 and to permit vertical adjustment of these members by threaded movement on the head portions 36.

An ornamental bottom rail 39 is mounted across the front edge of the base member 31, being secured in position thereon as by means of an angle iron bracket 40, which is fastened to the bottom member and to the front rail 39 as by screws 41 and 42. A pair of recesses are provided in the upper edge of the bottom rail 39 to receive a pair of pins 43, which are mounted in, and project slightly below, the bottom edge of a removable panel 44 which is adapted to close the space between the lower edge of the refrigerator cabinet door 13 and the base 31.

A spring catch 45 is provided on the inner face of the panel 44 and is adapted to engage a pin 46 which is mounted to project downwardly from the compartment bottom portion 18. The panel 44 may be mounted in position by inserting the pins 43 in the recesses in the upper edge of the rail 39, and then, by swinging the upper end of the panel 44 inwardly, the spring catch 45 may be forced into latched engagement with the pin 46. The panel may be removed by reversing this procedure.

Various types of insulating board may be used to make the pre-formed plasticized unit for my improved refrigerator cabinet, such for instance as the type made from shredded wood, corn or flax fibers or the like, the principal features required of this insulating material being that it shall have satisfactory insulating characteristics, and that it shall have sufficient mechanical strength to cooperate with the shell formed by the limited penetration of the plastic coating material which is applied thereto, to form, with the shell, a strong, light, completely self-supporting and hermetically sealed unit.

Various types of plasticizing material may be used, as for instance a phenol-formaldehyde plastic substance, soybean plastic, and others, the principal feature with respect to the plastic being that it shall have limited impregnation into the body of the insulating material comprising the unit, and shall provide a hard, smooth, moisture-impervious surface suitable for painting. The material also should be capable of withstanding the temperatures involved in the baking schedules of modern types of finishes, but since most plastics are cured at a temperature in excess of many of the suitable finishes, this factor is of merely incidental importance.

While I have illustrated a preferred embodiment of my invention, many modifications may be made without departing from the spirit of the invention, and I do not wish to be limited to the precise details of construction set forth, but desire to avail myself of all changes within the scope of the appended claims.

I claim:

1. A refrigerator cabinet formed by a combined side wall and top member of inverted U shape, a combined back wall and compartment bottom member of L shape, the L-shaped member having close interfitting engagement within the U-shaped member to form a forward opening food compartment, the legs of the U-shaped member extending downwardly below the bottom of the L-shaped member to form side enclosure walls of a storage compartment below the food compartment, and transverse horizontal tie rods extending in a medial plane through the horizontal

and vertical portions of the L-shaped member and through the vertical sides of the U-shaped member, and a bottom closure member secured transversely across the lower end of the storage compartment and having reinforcing connection with the side of the U-shaped member.

2. In a refrigerator construction, the combination of a side and top wall unit consisting of a single thick slab of rigid fibrous heat-insulating material having substantially right angle bends at the two upper corners thereof forming two side walls and a top wall, and a second back wall and bottom unit of the same material, comprising a single slab of sufficient width to fit in between the side walls and having a back wall portion located between the side walls and flush with the rear edge thereof and having a substantially right angle bend joining the back wall to the bottom wall for the refrigerator compart-

ment, said bottom wall extending between the side walls and having its forward edge flush with the forward edges of the side and top walls, means for securing said side walls in clamping relation to said back and bottom wall unit, said means comprising transverse horizontal tie rods extending in a medial plane through the horizontal and vertical portions of the back wall and through the vertical walls of the side walls, and a layer of initially plastic material covering and impregnating only to a predetermined degree the inner surface of said refrigerator compartment, and another similar coating on the outer surface of said refrigerator and all parts of said two units, the said plastic providing a relatively hard waterproof and air-tight coating on the external parts of said fibrous insulation and covering the joints between said units.
